UNITED STATES PATENT OFFICE.

GEORGE H. IRVING, OF HAYWARD, AND BRADLEY F. DURPHY, OF SAN FRANCISCO, CALIFORNIA, ASSIGNEES, BY DIRECT AND MESNE ASSIGNMENTS, TO FORDZONE MANUFACTURING COMPANY, OF SAN FRANCISCO, CALIFORNIA, A CORPORATION OF CALIFORNIA.

OIL-BURNER.

1,317,448.

Specification of Letters Patent. Patented Sept. 30, 1919.

Application filed March 13, 1919. Serial No. 282,319.

To all whom it may concern:

Be it known that we, GEORGE H. IRVING and BRADLEY F. DURPHY, citizens of the United States, residing at Hayward, in the county of Alameda and State of California, and city and county of San Francisco, State of California, respectively, have invented new and useful Improvements in Oil-Burners, of which the following is a specification.

This invention relates to oil burners, and particularly to a burner of the Bunsen type which is adapted to handle low gravity oils.

One of the objects of the present invention is to provide a combination burner and gas generator capable of handling low gravity oils, such as kerosene, distillate, and the like, which is adapted to operate on the Bunsen principle and which insures comparatively perfect combustion and avoids soot or carbon formations. Another object of the invention is to provide a gas generating attachment of novel construction, and, in conjunction therewith, a pilot light and generator which permit instantaneous lighting of the burner whenever required. Further objects will hereinafter appear.

The invention consists of the parts and the construction, combination and arrangement of parts hereinafter more fully described and claimed, having reference to the accompanying drawings, in which—

Figure 1 is a central, vertical section of the burner.

Fig. 2 is a detail view of the nozzle and the valves regulating the flow to the same.

Fig. 3 is a plan view of the burner.

Referring to the drawings in detail, A indicates a mixing tube of suitable construction, 2 a nozzle, in this instance positioned near the lower end of the mixing tube, 3 a gas generating chamber, 4 an auxiliary gas generating tube and 5 a primary gas generating tube. The generating chamber 3 may be cast integral with the mixing tube A or otherwise secured to the same. It is here shown as positioned near the upper end of the tube and is supplied with oil by means of the primary generating tube 5 which is connected at one end with an oil supply pipe 6, as shown at 7, and at the opposite end with the generating chamber 3, as at 8. Oil may be delivered to the tube 6 from

any suitable source of supply and the flow through said tube is, in this instance, more or less checked as it is filled with gravel 9, pumice stone or other material which insures a uniform flow.

The upper end of the tube 6 is secured or screwed into an extension 10 formed on the lower side of the generating chamber 3 and does not communicate with the chamber except through the primary tube 5, which is connected with the tube 6, as shown at 7, and with the generating chamber 3, as at 8. All oil admitted to the generating chamber 3 must therefore pass through the tube 5, which, in this instance, is coiled-shaped, said coil consisting of an upper and a lower section, as shown at 5 and 5'. This coil is at all times exposed to the flame of the burner, as will hereinafter be described, and it therefore delivers the oil in the form of vapor to the chamber 3. It escapes from the chamber 3 through a pipe 11 which is connected with the nozzle 2, the flow through said nozzle being regulated by a pair of needle valves 12 and 13. The valve 12 controls the escape directly through the nozzle tube 2, while the valve 13 serves the function of entirely closing off the flow when it is desired to shut down the burner. The pipe 11 communicates with a passage which is adapted to be opened and closed by the valve 13, and, as this passage is offset, as shown at 14, (see Fig. 2) with relation to the central passage through which the needle valve 12 extends, it is necessary to form a communicating port 15. The gas admitted through the tube 11 therefore passes by valve 13, then through port 15 and finally into the central passage and by the valve 12 where it discharges through the tip 2 directly into the lower end of the mixing tube.

The jet action thus produced induces an upward current of air through the mixing tube, thus forming a homogeneous mixture of air and gas which could be ignited at the upper end of the tube. A spreader plate or cap 16 is, however, employed in the present instance. This cap is provided with a series of perforations 17 at the upper end and a series of perforations 18 at the lower end. The gas delivered by the mixing tube will thus discharge through the perforations 17 and 18 and therefore, when ignited, will

produce a series of superposed flames such as is produced by most forms of gas burners. The amount of air admitted to the lower end of the mixing tube is regulated by a perforated cap 19. This cap, when turned about the lower end of the mixing tube, increases or decreases the area of the inlet opening 20 formed about the nozzle 2, thus regulating the quantity of air admitted.

10 The auxiliary generating tube 4 consists of a coil which is positioned interior of the cap 16 and directly on top of the generating chamber 3. Both ends of this coil are connected with the generating chamber 3, the 15 outer end being connected to the chamber 3, as at 21, and the inner end of the coil with the chamber, as at 22. This coil is merely provided for the purpose of increasing the area exposed to the heat, thus insuring a 20 perfect generation of gas and a liberal quantity of the same if a large flame is required.

For the purpose of avoiding the necessity of preheating the burner at all times when it is desired to use the same, we provide a generating coil, such as shown at 24. This coil surrounds the upper end of the mixing tube A and is cone-shaped, as shown (see Fig. 1). The upper end of the coil is connected with the generating chamber 3 through a tube 25, while the lower end of the generating coil is connected with the chamber 3 through a tube 26. The upper portion of the coil is perforated, as at 27, to permit gas to escape therefrom. This coil may be perforated at 35 one or more points, and, as these perforations are formed in the lower side of the coil, it can readily be seen that two or more flame jets will be formed which serve the function of maintaining the coil 24 sufficiently hot to 40 generate gas for the pilot flame produced by the gas escaping through the perforations 27. The heat from the pilot jets also serves the function of partially heating the auxiliary generating coil 4, thus further insuring a 45 sufficient supply of gas to operate the pilot jets or flames when the main burner is not in operation.

The operation of the burner in general will be as follows: When starting with an 50 entirely cold burner, it is first necessary to fill the priming cup, shown at 30, with oil. This oil is ignited with a match and the flame produced heats the nozzle 2, the tube 11 and the generator 3. Oil admitted 55 through the tube 6 after the generator has been sufficiently heated will therefore pass through the primary generating coil 5 and enter the generating chamber 3 through the connection 8. It will here immediately 60 flash into gas and discharge through tube 11 and nozzle 2 into the mixing tube from where it finally escapes through the perforations 17 and 18, where it may be ignited by means of a match. The oil contained in the primary 65 generating coil 5 will soon change to a gas,

as this coil is at all times exposed to the intense heat of the flames discharging through the perforations 17 and 18. Practically all generation of gas will therefore take place in the primary coil, as the oil is first admitted thereto, and, as this coil only surrounds the burner and is mounted exterior of the same, it can readily be seen that it can be easily removed if choked with carbon deposits and the like. Furthermore, it should be appreciated that any carbon formation which may have a tendency to form will be formed in this coil, thus preventing any carbon formation in the main generating chamber 3 or in the auxiliary generating coils 4 and 24.

Once the burner has been started it can readily be seen that it will be unnecessary to take the trouble to reheat the burner, as one or more pilot jets will be in operation within 75 the cap 16, that is, extinguishing of the main burner by shutting off valve 13 stops the main flow of gas through the nozzle 2, but it does not stop the flow of gas through the coil 24. Oil entering the same will therefore turn into a gas which will discharge through the perforations 27 and the jets thus produced will retain said coils sufficiently hot to operate the pilot jets. If it is therefore desired to start the burner at any time 80 it will only be necessary to open the valve 13, as the pilot jet generates sufficient gas to permit instantaneous starting of the main burner. The danger of fire and explosions heretofore so common in connection with oil 85 burners of this type is thus avoided, as there is no necessity of flooding the priming cup 30 and igniting the same when starting.

The burner constructed as here shown is simple and substantial in construction and 100 is provided with sufficient generating area to take care of any flame desired. The gas generated, being mixed with air in a manner similar to all Bunsen burner, insures a comparatively perfect combustion, thus avoiding 105 carbon deposits or sootting of the range or stove in which the burner may be installed. The provision of the primary generating coil 5 is of great importance in this instance as it prevents carbon deposits within the 110 burner proper, and, secondly, provides for a quick cleaning, renewal or removal whenever required without disturbing the mounting of the burner or any of the pipe connected therewith.

While a more or less specific construction is here shown we wish it understood that the materials and finish of the several parts may be such as the experience and judgment of the manufacturer may dictate.

Having thus described our invention, what we claim and desire to secure by Letters Patent is:

1. A combination burner and generator comprising a mixing tube, a gas generator 130

surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, and an auxiliary generating tube consisting of a series of coils surrounding the mixing tube above the generator, said auxiliary generator coil having its opposite terminal ends both connected with the generator.

20 2. A combination burner and generator comprising a mixing tube, a gas generator surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube consisting of a series of coils surrounding the mixing tube above the generator, said auxiliary generating coil having its opposite terminal ends both connected with the generator.

25 3. A combination burner and generator comprising a mixing tube, a gas generator surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube consisting of a series of coils surrounding the mixing tube above the generator, said auxiliary generating coil having its opposite terminal ends 30 both connected with the generator, a second auxiliary generating tube comprising a cone-shaped coil surrounding the upper portion of the mixing tube, said coil having its terminal ends connected with the generator and a series of perforations formed in the upper portion of said coil adapted to project a series of pilot flames downwardly against the lower portion of the coil.

35 3. A combination burner and generator comprising a mixing tube, a gas generator surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube consisting of a series of coils surrounding the mixing tube above the generator, said auxiliary generating coil having its opposite terminal ends 40 both connected with the generator, a second auxiliary generating tube comprising a cone-shaped coil surrounding the upper portion of the mixing tube, said coil having its terminal ends connected with the generator and a series of perforations formed in the upper portion of said coil adapted to project a series of pilot flames downwardly against the lower portion of the coil.

45 3. A combination burner and generator comprising a mixing tube, a gas generator surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube comprising a cone-shaped coil surrounding the upper portion of the mixing tube, said coil having its terminal ends connected with the generator and a series of perforations formed in the upper portion of said coil adapted to project a series of pilot flames downwardly against the lower portion of the coil.

50 3. A combination burner and generator comprising a mixing tube, a gas generator surrounding the tube, a nozzle positioned near the lower end of the tube, a tube connecting the nozzle with the generator, a source of oil supply, a primary generating tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube comprising a cone-shaped coil surrounding the upper portion of the mixing tube, said coil having its terminal ends connected with the generator and a series of perforations formed in the upper portion of said coil adapted to project a series of pilot flames downwardly against the lower portion of the coil.

tube surrounding the mixing tube, said primary generating tube being connected at one end with a source of oil supply and at the opposite end with the generator, a cap interior of the primary generating tube, said cap inclosing the upper end of the mixing tube, an annular series of radially disposed openings formed in the cap adapted to direct the flame produced by the discharging gas against the primary generating tube, an auxiliary generating tube comprising a cone-shaped coil surrounding the upper portion of the mixing tube, said coil having its terminal ends connected with the generator and being disposed within the cap, and a series of perforations formed in the uppermost portion of the coil adapted to direct a series of pilot flames against the remaining portion of the coil.

4. In a burner of the character described, a mixing tube, a generator surrounding said tube, a cap supported by said generator and inclosing the upper end of the mixing tube, a nozzle positioned at the lower end of the mixing tube, means for delivering oil to the generator, means for conveying the gas generated to the nozzle, an annular series of radially disposed openings formed in the cap to produce an annular series of radially discharging flames supplied with a combustible mixture formed in the mixing tube, a generating coil surrounding the upper end of the mixing tube and connected with the generator, a series of perforations in said coil adapted to project a series of pilot flames said flames serving the function of igniting the gas discharging through the flame openings in the cap and also serving the function of heating the generating coil, and a primary generating coil surrounding the cap and positioned so as to be exposed to the main flame of the burner, said generating coil being connected at one end with a source of oil supply and at the opposite end with the generator.

In testimony whereof we have hereunto set our hands in the presence of two subscribing witnesses.
